FOUNTAIN PEN

Ejnar Erik Ejerson, Stockholm, Sweden

Application January 28, 1944, Serial No. 519,989
In Sweden December 30, 1942

4 Claims. (Cl. 120—42)

The fountain pens now to be had in the market are provided with some mechanism for filling the ink container. Yet this mechanism has always considerably increased the price of the pen, and moreover, even if it has been effective, required too much space. However, the time during which a fountain pen can be used without refilling being the feature substantially determining the efficiency of the pen, any filling mechanism, in addition to increasing the price of the pen, reduced the said efficiency.

As pointed out above, the effective and comfortable filling of the ink container does not increase the efficiency of the pen, but the said efficiency should be determined by the fact that almost the whole available space in the pen can be filled with ink.

However, the above mentioned drawbacks are eliminated by the present invention. The fountain pen according to the invention is substantially characterized by the fact that the ink container consists of a replaceable member detachably connected with the pen nib holder and consisting of a tube provided with a bottom, an annular packing being disposed at the mouth of the said tube, the ink channel, located in the ink conductor plug of the pen nib holder and leading to the pen nib, beginning in a sleeve-shaped member preferably provided with an annular edge which is adapted to rest tightly against the said packing. Thus, the pen in question has no filling mechanism whatsoever, and therefore the whole container can be used for receiving ink. The container may be placed in a tubular protection casing which is detachably connected with the member carrying the pen nib by means of threads engaging one another, and in which casing there is located a spring holding the container pressed tightly against the edge of the sleeve shaped member. Further, the container is provided with threads adapted to receive a closing plug with corresponding threads. Consequently, filled containers can be sold and consumed containers can be easily replaced by new, filled containers. The member carrying the pen nib, or the sleeve-shaped part of the said member is provided with threads adapted to cooperate in such a way with the threads provided in the container and intended for the closing plug that the edge can be made to rest tightly against the packing of the container. Finally, the annular packing, which is preferably made of rubber or other yielding material, can be carried by an annular plate or the like made of stiff material, said plate being provided with threads and

screwed into the container threads for the closing plug.

Three embodiments of the invention are illustrated on the accompanying drawings:

Fig. 1 is a vertical section of a fountain pen according to one embodiment, and Fig. 2 a side view of a container intended for the said pen.

Fig. 3 shows, in vertical section, part of a pen according to the second embodiment, and

Figs. 4 and 5 show a pen according to the third embodiment in section, and a container for the said pen in side view, respectively.

In the drawings, the reference character 1 indicates the pen nib holder and 2 the ink container in the shape of a tube provided with bottom. As is seen from Figs. 2 and 5, the ink container is provided with threads adapted to receive a closing plug 3 as well as an annular plate 4 of stiff material, the said members 3, 4 being thus provided with threads corresponding to the threads of the tube. The plate 4 serves as a basis for an annular packing 5 which is preferably made of rubber. When the container 2 is connected with the holder 1, the said packing is intended to rest tightly against a member 6 provided with an annular edge 6'. In the said member there is inserted the ink conductor plug 8 which is provided with an ink channel 7. The conical end of the said plug facing the container extends some distance through the apertures of the packing 5 and of the plate 4, respectively.

In order to obtain the above mentioned tightening between the edge of the member 6 and the packing 5 the container 2, as shown in Fig. 1, can be located in a protection casing 9 which is connected with the member 1 by threads, and in which casing a spring 10 presses the packing 5 of the container 2 against the edge of the member 6. Another method, as shown in Fig. 3, is to provide the member 6 with threads adapted to cooperate with the threads in the container 2 and, by screwing together the said members, to obtain a tight contact between the packing 5 and the annular edge of the member 6. In the embodiments according to Figs. 1 and 3 the size of the container 2 will be determined by the inner space afforded by the protection casing 9. However, the last mentioned casing can be completely omitted, as is seen from the embodiment according to Fig. 4, in which embodiment the container 2 is screwed direct on to the earlier mentioned threads of the member 1, and the container 2 forms the shaft of the pen.

It is clear from the above statements that the

fountain pen according to the invention is very cheap due to its very simple construction, but that it will function satisfactorily in spite of this. No leakage between container and pen nib holder need occur since, due to the plate 4, the annular edge of the member 6 can be pressed against the packing 5 at a satisfactory pressure.

Obviously the pen can be filled quickly, comfortably and without difficulty. Due to its larger ink contents the pen according to the embodiment in Fig. 4 can be used with great advantage in offices and at school. The pen provided with a protection casing according to Figs. 1 and 3 is an excellent vest pocket pen because the container is better protected and the protective casing resembles the fountain pens now used.

Several embodiments are possible in addition to those described above and disclosed on the accompanying drawings without going beyond the scope of the invention.

Having now described my invention, what I claim as new and desire to secure by Letters Patent is:

1. In a fountain pen comprising a replaceable and removable ink container, a pen nib holder and an ink conducting plug for conducting ink from the container to the nib holder a cen-

trally apertured plate member closely fitting the interior of the lower portion of said container, a packing member abutting said plate and having an aperture in registry with the aperture in said plate, an ink conductor carried by the pen nib holder and having a portion extending through the aligned apertures in said packing and plate and a plug member integral with said pen nib holder having a bore through which the ink conductor extends and further having a circular edged portion firmly contacting said packing.

10 2. A fountain pen as claimed in claim 1 having a casing or barrel surrounding said ink container and provided at its lower end with a threaded portion with which the said plug is threadedly engaged.

15 3. A fountain pen as claimed in claim 1 having the lower portion of the container interiorly screw threaded and the said plate and packing provided with exterior threads to engage with the interior threads of the container.

20 4. A fountain pen as claimed in claim 1 having the lower portion of the container interiorly screw threaded and the said plug member exteriorly screw threaded to engage with the interior threads of the container.

EJNAR ERIK EJERSON.
